(57) **CLAIM**

The ornamental design for a straight hair curler, as shown and described.

DESCRIPTION

FIG. 1 is a perspective view of a straight hair curler showing my new design.

FIG. 2 is a second perspective view of FIG. 1, viewed in another aspect.

FIG. 3 is a front view thereof.

FIG. 4 is a back view thereof.

FIG. 5 is a left view thereof.

FIG. 6 is a right view thereof.

FIG. 7 is a top view thereof; and,

FIG. 8 is a bottom view thereof.

The broken lines in the drawings depict portions of the straight hair curler that form no part of the claimed design.

1 Claim, 8 Drawing Sheets
